JAR SEALING DEVICE OR THE LIKE

Joseph R. Fleisch, Oak Park, Ill., assignor to The Aridor Company, Chicago, Ill., a corporation of Illinois

Application March 13, 1942, Serial No. 434,473

5 Claims. (Cl. 226—82)

This invention relates to a jar sealing device or the like more particularly of the class described in the Safranski and Millenaar Patent No. 2,295,692 embodying an exhaust bell and mechanism including a turntable for raising and lowering the bell.

The present invention aims, among other objects, to permit the use of an overhead track for depressing the plunger carried by the bell for sealing the food container or the like within the bell, while, at the same time, and even during such movement, permitting manual adjustment from the exterior of the bell of the overall length of the plunger, thus effecting a saving of time and labor in the operation of the device and its adaptability to varying sizes of containers and eliminating shut-downs of the machine therefor.

This, together with other objects and advantages, will be apparent from the following description, taken together with the accompanying drawing, in which—

Figure 1 is a fragmentary elevational view, partially in section, of an exhaust bell and mechanism including a turntable for raising and lowering the bell, together with associated parts;

Figure 2 is an enlarged axial view of the bell of Fig. 1, being a partial section taken on the line 2—2 of Fig. 1; and

Figure 3 is a section, slightly reduced in size, taken on the line 3—3 of Fig. 2.

Referring in detail to the illustrative construction shown in the drawing, the exhaust bell 10, in the form of a metal hood, is here shown carried by a turntable 11 mounted to revolve on a base 12. There may be several of the bells 10 spaced circumferentially about the turntable. The turntable is secured as by screw-bolt 11a to a ring gear 11b to revolve on the deck 13 of the base by means of any suitable source of power (not shown) which may be connected to the drive shaft 14, the latter having a pinion 15 thereon meshing with peripheral teeth 16 on the ring gear 11b. The ring gear 11b is held in place on the base 12 by a central stationary turret 17 on the base which is secured to the deck 13 as by screw-bolts 17a. The turntable has a turret 18 which is arranged telescopically with respect to the stationary turret 17 and which revolves thereabout with the turntable 11, the revolving turret 18 being suitably secured to the turntable as by a lug and notch connection 19.

The drive shaft 14 may have another pinion 20 thereon engaging a large gear 21 keyed to a shaft 22 which passes centrally through the stationary turret 17 and terminates in a revolving

header 23 at the top thereof. The revolving header 23 carries a number of flexible pipes 24, one of which is connected with each of the bells 10, only one bell and pipe being here shown. The revolving header 23 mates face to face with the stationary valving block 25 suitably secured to the upper part of the stationary turret 17 and through which the shaft 22 revolvably passes. The revolving header 23 is keyed to revolve with the shaft 22 and is resiliently pressed against the valving block by a substantially heavy coil spring 26 held in place on the shaft 22 by a washer 27 and nut 28.

It will be understood that the revolving header 23 and valving block 25 have ports 29 and 30 therein respectively which are vertically aligned in a given orbital position of the turntable to place the flexible pipe 24 in communication with a fixed exhaust pipe 25a carried by the stationary turret 17 and its base 12. The fixed exhaust pipe 25a may be connected to any suitable exhaust pump (not shown) for withdrawing air from the bell 10. It will be understood also, that later in its orbit the revolving header port 29 may be placed in communication with a relief port (not here shown) in the valving block.

Each of the bells 10 is raised during the orbital movement of the turntable, first to permit a food container or the like 31 (Fig. 2) to be placed 30 under the bell, in a portion of the orbit of the turntable not felt necessary to be here shown, and is then lowered over the container 31. Means for this movement are provided by a cam groove 32 on the periphery of the stationary turret 17 which receives a roller 33 on an extension 34 of the bell 10. To permit this vertical movement of the bell as it revolves about the base with the turntable, the turret part 18 of the turntable has a vertically extending slot 35 there- 35 in through which the extension 34 passes, and the extension 34 may be elongated in the slot 35 and in the direction thereof so as to prevent rotation of the bell with respect to the turntable 40 during its movement under the influence of the cam groove 32 and cam roller 33.

In accordance with the present invention, the bell 10 carries a plunger 36 for pressing the cap 37 onto the food container 31 and which is manually adjustable from the exterior of the bell to vary the length of the plunger to suit different heights of containers while at the same time being engageable by an overhead track 38 to depress the plunger. The track 38 is carried by the base 12 as by screw-bolts 39 passing through a horizontal bracket part 40 of the track into the

upper face of the stationary turret 17. It will be understood that the overhead track 38 is located, in the orbit of the turntable, in the vicinity of the lowermost run of the cam groove 32 so that when the bell approaches this point in its orbital movement, a roller 41 carried by the plunger passes under and into engagement with a cam surface 42 on the under face of the track 38 which by its downward inclination gradually depresses the roller 41 as the bell revolves and moves farther under the track 38. At this time the bell has already been moved into substantially air-tight engagement with the turntable 11 by the cam groove and roller 32-33, as shown in the drawing, a rubber gasket 43 about the lower edge of the bell closing its lower, open end.

The roller 41 is here shown carried by the plunger 36 through the intermediation of a vertically slideable bearing member 44 in which the ends of the roller pintle 45 are journaled, the ends of the pintle 45 projecting therebeyond to play in vertical elongated slots 46 in the reduced upper end 47 of the bell 10. A coil spring 48, interposed between downwardly facing shoulders 49 on the bearing member 44 and upwardly facing shoulders 50 in the interior of the bell reduced end 47, urge the bearing members 44 and with them the roller 41 toward the upper end of the slot 46, thus elevating the plunger 36 except when the cam surface 42 of the overhead track depresses the roller against the action of the spring.

Still following the present invention, the plunger 36 has a part 51 within the bell, adapted to engage the container, and a part 52 which, by means of the bearing members 45 and roller 41, extends above the bell 10 in the sense that when the bell is beneath the track 38 the track does not engage the bell directly but through the intermediation of the roller 41. In this instance, the part 52 is in the form of a socket interiorly fully threaded as at 53 and the part 51 has a shank provided with external threads 54 by which the parts 51 and 52 are threadedly interengaged, the shank screwing into the socket, both to hold the parts together and also to determine the overall vertical length of the plunger 36, of which the parts 51 and 52 are portions, by the extent to which they are so threadedly interengaged.

As the plunger 36 moves downwardly under the influence of the track 38, the plunger part 52 slides in the packing gland 55 which is held in place by the exteriorly threaded collar 56 screwed into the throat of the bell 10 as at 57 to maintain the packing gland in position under compression and thus make the bell substantially air-tight while permitting the vertical movement of the plunger. Final downward movement of the plunger, just subsequent to its positions shown in Fig. 2, is accomplished by a further downward inclination 42a of the overhead track 38, which thus seals the jar cap 37 onto the container 31 while the bell is evacuated.

At its lower end, the plunger part 51 is flanged as at 58 to support the sealing disk proper 59 which directly contacts the container cap 37. The flange 58 and the sealing disk 59 are held loosely together by distance screws 60, say three in all, spaced about the circumference of the flange, each of which has a shouldered shank 61 reduced at its lower end where it is threaded as at 62 to screw tightly into the disk 59 without clamping the latter against the flange 58, the screw shank 61 passing slidably through the latter. Spaced circumferentially between the dis-

tance screws 60 are compression springs 63, also conveniently three in all, which urge the flange 58 and sealing disk 59 apart to the extent permitted by the distance screws 60, so as to compensate for irregularities in the levels of the tops of the caps 37.

It will be seen that the plunger part 52 is not permitted to rotate with respect to the bell 10 by reason of the arrangement shown, and in order to permit rotation of the plunger part 51 with respect to the plunger part 52, to adjust the overall length of the plunger, I have shown one of the parts 58-59 and in this instance the disk 59, in the form of a gear wheel by being provided with gear teeth 64 on its periphery which mesh with the teeth 65 of an elongate pinion 66, the teeth 65 being themselves vertically elongated as well as the pinion as a whole, as shown. To house the pinion in this relationship with the gear teeth 64, the bell 10 may be laterally enlarged as at 67 for the pinion 66, the enlargement 67 at its lower end forming a bearing for the trunnion 68 of the pinion. At its upper end, the pinion has a shank 69 which passes through a packing gland 70 disposed in the mouth of the enlargement 67 against a metal washer 71 at its lower end in abutment with an internal annular shoulder 72 in the bell enlargement, the metal washer 71 also holding the pinion against axial displacement. The packing gland 70 is held in position under compression against the washer 71 by a sleeve nut 73 which is exteriorly threaded to have threaded engagement as at 74 in the mouth of the enlargement. A knurled thumb-piece 75 may be disposed at the top of the pinion shank 69 secured in splined connection thereto as by a cap-screw 76 whereby rotation of the thumb-piece 75 will rotate the pinion 66, and, through the teeth 65 on the pinion and teeth 64 on the sealing disk 59, will rotate the plunger part 51.

By turning the thumb-piece 75 in a clock-wise direction the plunger part 51 may be rotated counterclockwise, which will screw the part 51 farther into the plunger part 52 and thus shorten the overall length of the plunger and vice versa, by turning the thumb-piece 75 in the opposite direction. The teeth 64 of the sealing disk are at all times free to slide vertically on the teeth 65 of the elongate pinion under the influence of the overhead track 38 and roller 41, so that the adjustment mechanism does not interfere with the operation of the device.

Thus, the normal height of the plunger within the bell, that is its height from the turntable 11 when underpressed and when the container 31 is first placed thereunder, may be varied to suit different heights of containers and this adjustment may be readily made from the exterior of the bell and even while the bell is under vacuum and the plunger is being depressed by the overhead track.

When it is desired to replace the plunger part 51 entirely and assuming that there is no container 31 in the bell, then the thumb-piece 75 may be rotated counterclockwise until the part 51 drops away from the part 52, having been entirely unscrewed therefrom. At such time the teeth 64 will slide down the teeth 65 until the plunger part 52 is entirely withdrawn from the bell. Thereafter, the same or another similar part 51 may be inserted in the bell, the teeth 64 meshed with the teeth 65 and then the part slid upwardly until it threadedly engages the part 52, when the thumb-piece 75 may then be rotated

clockwise to bring the part 51 to the desired elevation within the bell. It will be seen that at no time in the normal operation of the device is the plunger shank part 51 completely screwed into the socket plunger part 52, there being desirably at all times uninterengaged lengths of both the socket and the shank to permit adjustment by the pinion 65 either to increase or decrease the overall length of the combined plunger parts 51—52. Furthermore, at no time in the normal operation of the device are the teeth 64 out of mesh with the teeth 65 on the elongate pinion.

It is to be understood that the invention is not intended to be limited to details of construction here shown for illustrative purposes. Furthermore, it is not intended that it be understood that all features of the present disclosure must be used conjointly, since it will be apparent to workers in the art that various combinations or sub-combinations may at times be advantageously employed. For example, the device may well be useful in the absence of a vacuum in the bell.

Having described my invention, I claim:

1. In a jar sealing device or the like embodying a bell and mechanism including a turntable for raising and lowering the bell, the combination with a base for the turntable, of an overhead track carried by the base, a plunger carried by the bell, said plunger having a part within the bell adapted to engage a container to be sealed therewithin and a part extending above the bell adapted to engage the track to depress the plunger, said parts having threaded interengagement, means holding the part above the bell against rotation but permitting vertical movement thereof, and means carried by the bell and including a vertically elongated pinion, gear teeth on the plunger part within the bell engaging said pinion, and a manually operable member on the exterior of the bell for rotating the pinion and thereby the plunger part within the bell while permitting vertical movement of the latter whereby rotation of the latter moves the parts toward or from each other to vary the normal height of the plunger within the bell.

2. In a jar sealing device or the like embodying a bell and mechanism including a turntable for raising and lowering the bell, the combination with a base for the turntable, of an overhead track carried by the base, a plunger carried by the bell, said plunger having a part within the bell adapted to engage a container to be sealed therewithin and a part extending above the bell adapted to engage the track to depress the plunger, said parts having threaded interengagement, means holding the part above the bell against rotation but permitting vertical move-

ment thereof, and means carried by the bell and including a manually operable member on the exterior of the bell for rotating the part within the bell while permitting vertical movement thereof whereby rotation of the latter moves the parts toward or from each other to vary the normal height of the plunger within the bell.

3. In a jar sealing device or the like embodying a bell and mechanism including a turntable for raising and lowering the bell, the combination with a base for the turntable, of an overhead track carried by the base, a plunger having a part within the bell adapted to engage a container to be sealed therewithin and a part extending above the bell adapted to engage the track to depress the plunger, said parts having threaded interengagement, means holding one of said parts against rotation but permitting vertical movement thereof, and means for rotating the other of said parts but permitting vertical movement thereof whereby rotation of the latter moves the parts toward or from each other to vary the normal height of the plunger within the bell.

4. In a jar sealing device or the like embodying a bell, the combination with a plunger carried by the bell, said plunger having a part within the bell and a part extending above the bell, said parts having threaded interengagement, of means holding the part above the bell against rotation but permitting vertical movement thereof, and means carried by the bell and including a vertically elongated pinion, gear teeth on the part within the bell engaging said pinion, and a manually operable member on the exterior of the bell for rotating the pinion and thereby the part within the bell while permitting vertical movement of the latter whereby rotation of the latter moves the parts toward or from each other to vary the normal height of the plunger within the bell.

5. In a jar sealing device or the like embodying a bell and mechanism including a turntable for raising and lowering the bell, the combination with a base for the turntable, of an overhead track carried by the base, a plunger carried by the bell, said plunger having a part within the bell adapted to engage a container to be sealed therewithin and a part extending above the bell adapted to engage the track to depress the plunger, and means carried by the bell including a manually operable member on the exterior of the bell for adjusting the overall length of the plunger to vary the normal height of the plunger within the bell while permitting vertical movement thereof during said adjustment.

JOSEPH R. FLEISCH.
